UNITED STATES PATENT OFFICE.

WILLIAM MAXWELL, OF BLOOMINGTON, ILLINOIS.

RAILROAD-GATE.

1,210,190.

Specification of Letters Patent.

Patented Dec. 26, 1916.

Application filed February 29, 1916. Serial No. 81,143.

To all whom it may concern:

Be it known that I, WILLIAM MAXWELL, a citizen of the United States, and a resident of Bloomington, in the county of McLean and State of Illinois, have invented a new and Improved Railroad-Gate, of which the following is a full, clear, and exact description.

The object of the invention is to provide a new and improved railroad gate more especially designed for use on grade crossings and arranged to automatically sound an alarm and to subsequently close the normally open gates and hold the same closed by an approaching train until the latter has passed the crossing, and to then automatically return the gates to normal open position.

Another object is to readily permit the use of the operating devices for the gate on single or multiple track railroads.

In order to accomplish the desired result, use is made of a pivoted barrier normally held locked in open position and adapted to swing into closed position by its own weight, an actuating device, a counterweight device for returning the barrier to upright position and normally holding it thereon, an actuating device along the track at one side of the crossing and a distance therefrom to be actuated by an approaching train for actuating the said counterweight device to allow the barrier to swing into closed position, a locking device for locking the said counterweight device in position at the time the barrier is lowered, and a releasing device for the said locking device arranged along the track on the other side of the crossing to be engaged by the departing train after the latter has passed the crossing, to release the barrier and allow it to swing back into normal open position.

A practical embodiment of the invention is represented in the accompanying drawings forming a part of this specification, in which similar characters of reference indicate corresponding parts in all the views.

Figure 1 represents a plan view of my device as applied to a single track road and showing the gates in section; Fig. 2 is a side elevation of the same with the roadbed and crossing shown in section; Fig. 3 is a diagrammatic view of the releasing system for returning the gates to their normal raised position; Fig. 4 is an enlarged vertical section of one of the gate-operating devices at

the time the gate is open; Fig. 5 is a similar view of part of the same and with the parts in position when the gate is in lowered or closed position; Fig. 6 is a sectional plan view of the same on the line 6—6 of Fig. 4; Fig. 7 is an enlarged sectional side elevation of one of the gate-actuating devices for closing the gate; Fig. 8 is a cross section of the same on the line 8—8 of Fig. 7; Fig. 9 represents a side elevation of one of the releasing devices; and Fig. 10 is a cross section of the same on the line 10—10.

As shown in the drawings, Fig. 1 represents a single track embodiment of my invention, wherein 1—2 represent the rails of the track 3, constituting the crossing, which latter is controlled by barriers 8, preferably arranged in pairs, as shown in Fig. 1. The pairs of gates are normally in open raised position and are adapted to be closed automatically on a train approaching the crossing and adapted to return to raised normal position on the train departing from the crossing. The pairs of gates are connected with each other to operate in unison but only the pair of barriers 8 is connected with the gate-operating devices 5, 5 connected with the actuating devices 4, 4' and the releasing mechanism 6, 6' disposed along one rail of the single track on opposite sides of the crossing, as plainly indicated in Figs. 1 and 2. To the right of the track I arrange the devices 4 for operating the barriers 8, best indicated in Fig. 2, and on the opposite side of the crossing I arrange the device 6 which constitutes the releasing device for the barriers to bring them to the position indicated in Fig. 2 after the train has passed the barriers 8, 8' of the crossing. Should, however, the train pass in the opposite direction to that just indicated, the gate releasing device 4' will close the crossing to extraneous traffic and the gate returning device 6 on the same side of the crossing to 4' is arranged to become inoperative. The releasing device 6' is arranged to bring the barriers to the normal position indicated in Fig. 2, whereas with the train passing beyond and past the gate releasing device 4, this latter is inoperative to any train passing in the direction just outlined. Naturally a two-track road would necessitate a slight rearrangement of the devices referred to in conjunction with a single-track road. However, this modification is so patentably obvious that further reference thereto need hardly be made.

Since the gates and returning mechanisms are duplicated on both sides of the track, it will be sufficient to describe one set of mechanism, it being understood that suitable interconnections are made where a plurality of these devices are intended to operate simultaneously.

Turning to Figs. 7 and 8, gate operating mechanisms, as indicated, are arranged contiguous to the track 2 and constitute spider members 14 arranged upon a shaft 15 journaled in a housing 15' on the one side and a housing 30' on the other, which housings are suitably mounted on foundations, which latter construction need not be further gone into. The spider arms 14 carry in the illustrated embodiment of my invention, rollers 14'' mounted upon the studs 14'''. In this way as the wheels of the train pass by the point of the track indicated in the figures, the spider arms are caused to rotate and thereby transmit their motion to a pinion 31 mounted upon the shaft 15, to a rack bar 32 moving in guideways 32' of the housing 30', and by means of the spring 34 connected at one end to the pin 34' on the rack bar 32 and on the other end connected by means of the pin and block 33' to the transmission rod 33, is enabled by means of the mechanism indicated in Fig. 4 to not only release the barriers 8 to stop all cross railroad traffic, but at the same time enables a storing of energy to take place to bring said arms back to their normal position at the proper time.

By reference to Fig. 1, it will be seen that in a single track road, it becomes necessary to make the spider arm inoperative with respect to the operating rod 33 when the train is passing in a particular direction. For this reason, a ratchet and pawl mechanism indicated by 30, is mounted with respect to the pinion 31 and the shaft 15. In order to facilitate the return of the rack bar 32 to its normal position, a spring 42 is attached at the one end to the pin 42' on the said rack bar and on the other end to a stud 43 mounted upon the housing 30'.

Turning to Fig. 4 it will be seen that the rod 33 is made integral with a rack 35 mounted on the housing 7 constituting the gate support. Said rack 35 has teeth 35', which are caused to engage with the pinion 38 mounted upon a shaft 44, which latter shaft has also mounted upon it a grooved pulley 45 having a flexible transmitting means 39 engaging with a double grooved flanged drum 19, loose on a shaft 9, journaled in the housing 7. In this way, when the rack 35 operates upon the pinion 38, motion is transmitted to the grooved and flanged drum 19 and by virtue of the cable 13 operating in one of the grooves 20 and being attached to a weight 16, the weight is raised and with it a tripper block 17 attached thereto. This tripper block in its

upward motion strikes against a fulcrumed lever 11, which engages with a notch 12 in a disk 10 secured to the shaft 9. Said barrier is normally arranged to tilt slightly forward, though counterbalanced by a weight 18, in order that on being released by the restraining lever 11, normally engaging with the notch 12, the barrier shall proceed to fall in a relatively easy manner. With the rotation of the grooved drum 19, the weight raised by the same, which would normally tend to make the said drum return to its original position when the movement of the rod 33 has ceased, is constrained to take up its modified position by means of a spring-pressed pawl 22 engaging with the segmented serrated teeth 21 arranged at the periphery of the said drum 19. The pawl member 22 is fulcrumed at 22' and is pressed to engage the periphery of the said drum by means of the spring 22''.

The flange of the drum 19 carries a pin or projection 23, which engages with a lug 24 carried by the disk 10. However, because the drum 19 rotates substantially a quarter of a revolution before the releasing block 17 strikes the weighted lever 11 to release the disk 10, the said disk and consequently the arm integral therewith, cannot turn through the corresponding angle to bring the arm to a horizontal position, but the drum 19 has substantially performed its function of raising the weight 16, which latter weight is used to turn the arm 8 to its normal operating position. Thus by means of a releasing system of cables 14' attached at one end to the pawl 22, by the movement of the cables to withdraw the pawl 22 from engagement with the drum 19, the said drum in returning to its normal position by virtue of the pin 23 engaging with the ear 24 of the disk 10 necessarily returns the arm 8 to its upright position when the cables 14' are caused to take the proper movement by means of the suitable mechanism indicated by the returning devices 6 and 6'. The said returning devices are better illustrated in Figs. 9 and 10 of the drawings. It will be seen that a roller 25 is mounted upon an arm 28' placed contiguous to the rail 2 and in suitable relationship to the railroad crossing 3. Said arm 28' is mounted upon a shaft 27 suitably supported on a foundation frame 46. Mounted integrally with the said shaft 27 is also an arm 28 which is attached to a dash pot device indicated at 29. The arm 28' is pressed to an operating position by means of the springs 26, suitably mounted between the frame 46 and the arm. On the other hand, the cable member 14' is attached to the upright arm 25'. Thus it will be seen that if the roller 25 should be struck in such a manner as to ease the cable 14', the dash pot device 29 will not allow the arm 25' to go

past the vertical neutral point and in this manner release the pawl 22 in Fig. 4 before its allotted time. On the other hand, should the roller 25 be struck by a wheel flange of 5 the train in the position so as to positively release the pawl 22, the dash pot device in no wise interferes in this normal operation. It will therefore be seen that the mechanisms described in Fig. 1 are designed to become 10 operative on a single-track road, but even without modification can be installed in a two-track road without having to resort to any modification of parts whatsoever.

In Fig. 2 I have indicated an arrangement 15 whereby the spider 14 operates the rack bar 32, in the one case mounted above the shaft 15, but in the other case below the shaft 15. This arrangement, however, hardly merits a separate view, since the housing and the 20 attached parts are exactly alike in both cases, but simply involve a different method of positioning the same with respect to the roadbed. On the other hand, in order that the barrier 8 indicated in Fig. 2 shall be 25 operative in opposite directions, it becomes necessary to change the arrangement of the flexible member 39 of Fig. 4 to that indicated by 41 in Fig. 2.

In Fig. 3 I have indicated diagrammatically 30 the manner of attachment of the cables 14' to the pawls 22 engaging with the teeth 21 of the respective drums 19. It will be seen that the cable 14' is bifurcated in such a manner that whereas one bifurcation operates one of the simultaneous set of pawls 22, the other bifurcation operates the second one. In this way, the interconnections between the sets of gates are all subjected to an equal strain.

40 Returning to Fig. 4, I have provided a spring 35'', which being connected suitably on the one end to the housing 7' and the rack 35 on the other, tends to return the rack 35 to its normal position when withdrawn therefrom by the rod members 33.

In order that the proper signal may be given to the roadway traffic at the crossing the rack 35 is caused to engage by means of its teeth 35' with the bell crank lever 36 50 to give suitable oscillatory movement to the striker of a bell 37, to sound the latter and which shall be indicative of the speed with which the spider arms 14 are being engaged by the passing train. The bifurcations indicated in Fig. 3 of the drawings are suitably supported by means of rollers 40 mounted in the housing 7 either directly or by means of the bracket 40'. The shafts 44 extend across the track, as plainly shown in 55

60 Fig. 1, and the shafts are connected by pulley and belt devices 39 and 41 with the shafts 9 carrying the barriers 8' to operate the same in unison with the barriers 8.

In the operation of the device, a train 65 passing from right to left in accordance with

the view indicated in Fig. 1 of the drawings, would strike the spider 14, which in turn would operate to firstly raise the weight 16 and secondly after having raised this weight a suitable height, would release the 70 gate arms 8 by means of the block 17 engaging with suitable fulcrumed levers 11, which lock the gate arms in their upright position. It will be noted that because the rack bar 32 only carries a definite number of 75 teeth irrespective of the length of the train and the actual number of rotations or impulses imparted to the spider, the weight 16 will not travel more than a definite amount. The same is also true with regard to the 80 rack 35. Moreover because the springs are arranged between the rods 33 and the rack 32, whatever shock might be present in the spider arms, would not necessarily be transmitted to the rods 33 and the remainder of 85 the system. The train in subsequently passing over the roller 25 on the same side of the crossing, causes no change in the operation of the arms, or for that matter in the system generally, whereas when the said 90 train has passed the crossing 3 and engages with the releasing mechanism 6 by striking the corresponding roller 25, the cables 14' are tensioned and thereby are made to release the pawls 22 engaging with the teeth 95 21 on the drum 19. On the other hand when the train subsequently engages with the spider arms 14 of the mechanism 4' indicated in Fig. 1, by virtue of the ratchet and pawl mechanism 30 indicated in Fig. 7, no action 100 takes place on the railroad gate. It will be seen therefore that whereas the signals given by the bell 37 by means of the rack 35 engaging with the bell crank lever 36, causes a signal indicative of the speed with which 105 the train is approaching, as soon as the arms are released, they fall in a manner entirely independent of the releasing mechanism and moreover the return of said arms is brought back to normal at a speed entirely independent of the crossing train. By this means 110 therefore the shock to the apparatus as a whole is considerably diminished, since the storing of energy has to take place by steps and therefore the individual parts need not 115 have momentum to cause any considerable danger or shock.

In case sidewalks extend across the track in addition to the roadway, then small barriers are connected with and operate in unison with the swing gates or barriers 8, 8'. 120

Having thus described my invention, I claim as new and desire to secure by Letters Patent:

1. A gate for railroad crossings, comprising a pivoted barrier normally held locked in open position and adapted to swing into closed position by its own weight, a counter-weight device connected with the barrier to normally hold the latter in open position 125 130

and to return the closed barrier to normal open position, an actuating device along the track at one side and a distance from the crossing and adapted to be actuated by an approaching train for actuating the said counterweight device to allow the barrier to swing into closed position, a locking device for locking the said counterweight device in position at the time the barrier moves into closed position, and a releasing device for the said locking device arranged along the track on the other side of the crossing to be engaged by the departing train after the latter has left the crossing to release the barrier and allow it to swing back into its normal open position, the said releasing device including a flexible member attached to the said locking device.

2. A gate for railroad crossings, comprising a counterweighted barrier mounted to swing by its own weight from normal raised position to closed position across the crossing, a drum loose on the pivot of the said barrier and provided with a pin, a disk rotating with the said pivot and having a projection engaged by the said pin, a countershaft having a pulley and belt connection with the said drum, a flexible member engaging the said drum, a weight attached to the said flexible member, a pinion on the said countershaft, a spring-pressed rack adapted to mesh with the said pinion, a second rack a distance to one side of the crossing and rigidly connected with the first-named rack, a revolute member controlled by an approaching train, a second pinion in mesh with the said second rack, and a pawl and ratchet mechanism connecting the said second pinion with the said revolute member.

3. A gate for railroad crossings, comprising a counterweighted barrier mounted to swing by its own weight from normal raised position to closed position across the crossing, a counterweighted drum loose on the pivot of the said barrier and provided with a pin, a disk rotating with the said pivot and having a projection engaged by the said pin, a countershaft having a pulley and belt connection with the said drum, a pinion on the said countershaft, a spring-pressed rack adapted to mesh with the said pulley, a second rack a distance to one side of the crossing and rigidly connected with the first-named rack, a revolute member controlled by an approaching train, a second pinion in mesh with the said second rack, a pawl and ratchet mechanism connecting the said second pinion with the said revolute member, a pawl and ratchet mechanism connected with the said counterweighted drum, and a releasing device along the track on the other side of the crossing and connected with the said pawl and ratchet mechanism of the counterweighted drum, the said releasing

device being controlled by the departing train.

4. A gate for railroad crossings, comprising a counterweighted barrier mounted to swing by its own weight from normal raised position into closed position, a shaft carrying the said barrier, a drum loose on the said shaft and having a pin and a notched segment, a notched disk fixed on the said shaft and having a lug engaged by the said pin, a flexible connection engaging the said drum and carrying a weight, a pawl engaging the notched disk, a block on the said flexible connection and adapted to engage the said pawl, an actuating device along the track at one side of the crossing and connected with said drum, a pawl engaging the said ratchet segment, and a releasing device along the track on the other side of the crossing and connected with the said notched segment and pawl.

5. In a device of the kind described, a gate, a gate operating means comprising a revolute member having arms arranged to receive successive impulses from an approaching train, mechanism for holding the gate normally in open position, the said mechanism being controlled by the impulses of the revolute member to permit the gate to close, and a unitary impulse gate returning means.

6. In combination a gate member, a locking means for locking the gate member in normal open position, a releasing means for the said locking means, the said gate member when released moving to closed position, means for returning the gate member to normal position and means connected with the returning means for operating the said releasing means.

7. In combination with the track of a railroad, a one-way gate operating mechanism comprising a gate controlling means including a revolute member operated by repeated impulses from the train in passing by said mechanism to permit the gate to close, and a one-way operable gate returning means also operable by said train.

8. In a device of the kind described, a gate controlling means operated by successive impulses from a passing train to permit the gate to close, a unitary impulse gate returning means, the said gate returning means including a spring controlled arm adjacent the rail and adapted to be engaged by a train, a shaft on which the arm is mounted, an arm mounted on said shaft, and a dash pot connected with said arm.

9. In combination with the track of a railroad, a one-way gate operating mechanism comprising a gate controlling means operated by repeated impulses from the train in passing by said mechanism to permit the gate to move to closed position, a locking device for said gate when in closed

position, a one-way operable gate returning means also operable by said train, said returning means comprising a member arranged along the track and provided with 5 a roller, springs for holding said member in normal vertical position, a shaft on which said member is mounted, an arm on said shaft, a dash pot connected with said arm, a second arm on said shaft, and a flexible 10 connection between the said second arm and the said locking device.

10. In a device of the class described, a gate member, a gate operating means comprising a revoluble actuating member, a 15 shaft on which said member is mounted, a pinion carried by said shaft, a rack in mesh with said pinion, a transmission rod connected by a spring with said rack, a second rack to which the transmission rod is 20 connected, a pinion actuated by the said second rack, a drum operatively connected with the said pinion, and means for connecting said drum with the gate member.

11. In a device of the class described, a 25 gate member, a gate operating means comprising a revoluble actuating member, a shaft on which said member is mounted, a pinion carried by said shaft, a rack in mesh with said pinion, a transmission rod connected by a spring with said rack, a second rack to which the transmission rod is 30 connected, a pinion actuated by said second rack, a drum mounted to turn and actuated from 35 the said second pinion, means for connecting the drum with the gate member, and a weight connected with the said drum.

12. In combination with a gate member, 40 a locking means for locking the gate member in open position, releasing means for said gate member comprising an energy storing device, means for actuating the same to store

energy, the said energy storing device having means for releasing the said locking means, after the energy is stored, to permit 45 the gate to close, a locking means for the said energy storing device when the gate member is in closed position, means for releasing the said locking means, and a connection between the said gate member and 50 the energy storing device for returning the gate member to normal position after the said locking means is released.

13. A gate for railroad crossings, comprising a counterweighted gate member mounted to swing by its own weight from normal raised position into closed position, a shaft carrying the said gate member, a drum loose on the said shaft and having a pin and a notched segment, a notched disk fixed on the 60 said shaft and having a lug engaged by the said pin, a flexible connection engaging the said drum and carrying a weight, a pawl engaging the notched disk, when the gate member is in raised position, means on the 65 flexible connection adapted to engage the said pawl to release the same, an actuating device along the track at one side of the crossing and connected with the said drum to turn the same to raise the said weight, 70 a pawl engaging the said notched segment of the drum, when the gate is in closed position, and a releasing device along the track on the other side of said crossing, the said releasing device including an arm mounted 75 to swing and a flexible member connecting said arm with the last mentioned pawl.

In testimony whereof I have signed my name to this specification in the presence of two subscribing witnesses.

WILLIAM MAXWELL.
